UNITED STATES PATENT OFFICE.

ALBERT A. PAGE, OF EAST HAVEN, CONNECTICUT, ASSIGNEE TO SARGENT & COMPANY,
OF NEW HAVEN, CONNECTICUT, A CORPORATION OF CONNECTICUT.

LOCK.

1,138,580.

Specification of Letters Patent.

Patented May 4, 1915.

Application filed November 11, 1914; Serial No. 571,508.

To all whom it may concern:

Be it known that I, ALBERT A. PAGE, a citizen of the United States, residing in the town of East Haven, county of New Haven, and State of Connecticut, have invented certain new and useful Improvements in Locks, of which the following is a full, clear, and exact description, when taken in connection with the accompanying drawing.

10 This invention relates to locks, and more particularly to latch bolt locks for school-houses and other buildings, having means operable by a key whereby the latch bolt may be dogged in its retracted position so that 15 when desired the door may be opened merely by pushing or pulling the same.

In an application filed December 2, 1913, Serial No. 804,215, I have described a lock having a latch bolt, a cylinder lock mechanism at the outside of the door for retracting the latch bolt, but inoperative to dog it in retracted position, and a cylinder lock mechanism at the inside of the door which will retract the latch bolt then dog it in retracted position.

20 My present improvements relate to a lock in which the cylinder lock mechanism at the inside of the room is inoperative to retract the latch bolt, but is, nevertheless, fully operative to dog the bolt in retracted position, after it has been retracted by the knob, thumb-piece, or other manual retracting means at the inside of the door. Hence in 25 order to dog the latch bolt in retracted position, the inside knob, or other retracting member, is manipulated to withdraw the bolt, and while the latter is held in retracted position a key is inserted into the lock from the inside of the door and rotated to dog the 30 bolt in its retracted position, after which the knob or other retracting member may be released without releasing the bolt.

To these and other ends, the invention consists in the novel features and combinations of parts to be hereinafter described and claimed.

35 In the accompanying drawings, Figure 1 is an elevation of a lock embodying my improvements, with the cap plate omitted, the 40 latch bolt being in the normal projected position; Fig. 2 is a similar view of the upper part of the lock, showing the latch bolt retracted by the outside key; Fig. 3 is a view similar to Fig. 1, showing the latch bolt

dogged in retracted position by the inside 55 key; and Fig. 4 is a reverse view of the upper portion of Fig. 3.

Referring to the drawings, the case 10 of the lock, having the face plate 11, contains a latch bolt 12 normally projected by a spring 13. The stem 14 of the latch bolt carries a crosshead 15, engaged by a lever 16, adapted to be operated by a lifter 17, which is in turn actuated by an inside thumb-piece or push-bar 18. The particular means for retracting 60 the latch bolt manually from the inside of the door is immaterial. Moreover, in the lock selected for illustration, the retraction of the bolt from the outside of the door is confined to the key, but this is likewise an 65 immaterial feature.

The means for retracting the latch bolt by means of a key from the outside of the door comprises a retracting lever 20, pivoted in the case at 21, and having one extremity 75 22 thereof engaged with the crosshead 15 of the bolt. A cylinder lock 22, secured in an opening in the case at the outside of the door, is provided with a bit, dog or rollback 23, adapted to engage the free end 24 80 of a lever 25, pivoted in the case at 26, which free end 24 loosely rests on and is supported by a lateral projection 27 on the upper end of the lever 20. Thus, when the rollback 23 is rotated in a counter-clockwise direction 85 with respect to Fig. 1, it will depress the lever 25 and swing the lever 20 to retract the latch bolt, as shown in Fig. 2.

The cylinder lock mechanism at the inside 90 of the door for dogging the latch bolt in retracted position comprises a cylinder lock 28, secured in an opening in the case at the inside of the door, and provided with a rollback 29. This rollback 29 co-operates with a detent lever 30, pivoted in the case at 95 31, and having an arm 32 adapted to be contacted at its upper extremity by the rollback 29 for the purpose of dogging and releasing the bolt. The detent lever 30 is also provided with a rearwardly extending 100 arm 33, adapted to co-operate with the cross-head 15, and with a downwardly extending lug or projection 34, which is also adapted to co-operate with said crosshead, as herein-after described.

105 The operation of retracting the latch bolt from the outside of the door has already been described. Obviously, the key actu-

ated means at the outside of the door cannot operate to dog the latch bolt in its retracted position. When it is desired to hold the bolt back in the case so that the door may be 5 freely opened merely by pushing or pulling the same, the inside thumb-piece or cross-bar 18, or its equivalent, is operated to retract the bolt, as shown by the dotted lines in Fig. 3. The key for the cylinder 28 is 10 then inserted into said cylinder and rotated to actuate the rollback 29 in such a manner as to move the detent lever 30 from the position shown in Fig. 1 to the position shown in Fig. 3. The rollback 29 contacts 15 with one face of the upper extremity of the arm 32, and moves the arm 33 down in front of the cross-head 15, thereby dogging the bolt in retracted position. When it is desired to release the bolt, the key is turned to 20 reverse the movement of the rollback 29, which will then contact with the opposite side of the arm 32 and move said arm in the opposite direction to release the bolt.

It will be apparent that the detent lever 25 30 is entirely independent of the retracting lever 20, for which reason the inside cylinder lock is inoperative to retract the latch bolt. In fact, the detent lever is blocked against movement when the latch bolt is in 30 the normal projected position, because at this time the crosshead 15 will be in line with the lug 34, as shown in Fig. 1, and upon attempting to turn the lever in a clockwise direction the lug 34 will abut the cross-head 15, and the detent lever will be thereby blocked against any appreciable movement. However, as soon as the latch bolt 35 has been retracted by the manual retracting means at the inside of the door, the detent lever 30 may be readily moved into its operative position by the key at the inside of 40 the door.

I have not attempted to illustrate the 45 usual pin tumblers with which the cylinder locks 22 and 28 are provided. If desired, these two cylinder locks may be actuated by the same key, but usually they will have different keys, and the janitor or proprietor will retain the key for the cylinder 28 so 50 that the latch bolt may not be dogged in retracted position by an unauthorized person. It will be apparent that, if desired, the latch bolt may be dogged in its 55 retracted position after it has been pushed inward from the face of the lock instead of retracted by the manual retracting means at the inside of the room, but usually it will be preferable to employ this last named means because it does away with the necessity of opening the door for gaining access to the bolt.

Without limiting myself to the precise construction shown, I claim:—

1. In a lock, the combination of a latch bolt, and a cylinder lock mechanism inoper-

ative to retract said bolt but operative to dog it in retracted position; substantially as described.

2. In a lock, the combination of a latch bolt, manual retracting means therefor, key- 70 actuated means at the outside of the door for retracting said bolt, and a cylinder lock mechanism at the inside of the door for dogging said bolt when it is held retracted by said manual retracting means, said cylinder lock mechanism being inoperative to retract the bolt; substantially as described.

3. In a lock, the combination of a latch bolt, key-actuated means at the outside of the door for retracting said bolt but inoperative 80 to dog it in retracted position, manual retracting means for the bolt at the inside of the door, and key-actuated means at the inside of the door inoperative to retract the bolt but operative to dog it in retracted position when it is retracted by said manual retracting means; substantially as described.

4. In a lock, the combination of a latch bolt, key-actuated means for retracting the same from the outside of the door, manually 90 operable means for retracting said bolt from the inside of the door, a cylinder lock at the inside of the door, and a dogging lever for said latch bolt adapted to be actuated by said cylinder lock and independent of said first 95 named key-actuated means; substantially as described.

5. In a lock, the combination of a latch bolt, key-actuated means for retracting the same from the outside of the door, manually 100 operable means for retracting said bolt from the inside of the door, a cylinder lock at the inside of the door, and a dogging lever for said latch bolt adapted to be actuated by said cylinder lock and independent of said 105 first named key-actuated means, said dogging lever being inoperative to retract the bolt but being operative to dog it in retracted position; substantially as described.

6. In a lock, the combination of a latch 110 bolt, pin tumbler mechanism having two rollbacks, a retracting lever for said latch bolt co-operating with one of said rollbacks, and a detent lever for dogging said latch bolt in retracted position co-operating with 115 the other rollback, said levers entirely independent of each other; substantially as described.

7. In a lock, the combination of a latch bolt, a cylinder lock having a rollback, a second cylinder lock having a rollback, a retracting lever for said latch bolt operable by one of said rollbacks, and a detent lever for dogging said latch bolt in retracted position operable by the other rollback, said 120 levers having independent movement in both directions; substantially as described.

8. In a lock, the combination of a latch bolt, key-actuated means at one side of the door for retracting said bolt but inoperative 130

to dog it in retracted position, and key-actuated means at the opposite side of the door inoperative to retract the bolt but operative to dog it in retracted position; substantially as described.

9. In a lock, the combination of a latch bolt, a cylinder lock mechanism at the outside of the door for retracting said bolt but inoperative to dog it in retracted position, 10 and a cylinder lock mechanism at the inside of the door inoperative to retract the bolt but operative to dog it in retracted position; substantially as described.

10. In a lock, the combination of a latch bolt, pin tumbler mechanism having two rollbacks, means actuated by one of said rollbacks to retract said bolt but inoperative

to dog it in retracted position, and means actuated by the other rollback to dog said bolt in retracted position but inoperative to 20 retract the same; substantially as described.

11. In a lock, the combination of a latch bolt, key-actuated means at the outside of the door for retracting said latch bolt, and key-actuated means at the inside of the door 25 inoperative to retract said latch bolt but operative to dog it in retracted position; substantially as described.

In witness whereof, I have hereunto set my hand on the 9th day of November, 1914. 30
